FIREBOX AND COMBUSTION CHAMBER
CONSTRUCTION

Harry A. Lacerda, Green Island, N. Y.

Original application November 1, 1940, Serial No.
363,905. Divided and this application October
20, 1943, Serial No. 506,936

2 Claims. (Cl. 110—87)

This invention relates to improved fire-box and combustion chamber construction and particularly to constructions of this character for use in connection with locomotives, the subject matter being a division of my co-pending application, Serial No. 363,905, filed November 1, 1940, now Patent 2,335,152, dated November 23, 1943.

It is a particular object of the invention to provide an efficient economical fire-box and combustion chamber construction in which cinder cutting of the wrapper, crown and tube sheets and clogging of the tubes and tube sheet is reduced to a minimum.

A further object is the provision of an improved baffle wall for the combustion chamber to prevent or minimize clogging of the tubes and cinder cutting of the tube sheet, wrapper sheet, and tubes.

Another object is the provision of an improved deflector above the fire-box door hole which deflects the coal downwardly into the fire-box thereby protecting the crown sheet from cinder cutting and preventing the flue holes from clogging and at the same time causing increased efficiency in combustion.

Another object of the invention is to provide in conjunction with a fire-box and a combustion chamber a brick arch, baffle wall and/or a deflector plate constructed and arranged to assure direct flow of the fuel from the door hole into the fire-bed under said arch at the rear of the latter, to thereby imprison the turbulence and to retard the gases in the fire-box regardless of the draught at various speeds of the locomotive, and also to keep cinders and slag from traveling over the arch to the tube sheet and tubes to eliminate cinder cutting of these parts.

For a fuller understanding of the invention, reference should be had to the accompanying drawings in which—

Fig. 1 is a longitudinal sectional view through the fire-box and combustion chamber and a portion of the boiler of a locomotive illustrating one embodiment of my invention;

Fig. 2 is a sectional view in the direction of the arrows on the line 2—2 of Fig. 1;

Fig. 3 is a sectional view in the direction of the arrows on the line 3—3 of Fig. 1;

Fig. 4 is a top plan view of a portion of the brick arch;

Fig. 5 is a sectional view in the direction of the arrows on the line 5—5 of Fig. 4;

Fig. 6 is a perspective view of one of the bricks employed in the brick arch;

Fig. 7 is a perspective view of one of the bricks

used in the top row or course of the brick arch;

Fig. 8 is a perspective view of one of the bricks used in my improved baffle wall;

Fig. 9 is a perspective view of a T-iron that may be used in fastening the baffle wall in position;

Fig. 10 is a view in elevation of a modification of the baffle wall in which the baffle wall is extended completely around the wrapper sheet of the combustion chamber;

Fig. 11 is a sectional view on the line 11—11 of Fig. 10;

Fig. 12 is a perspective view of the channel iron that may be used in holding the vertical and inverted portions of the baffle wall in position;

Fig. 13 is a view of a modified form of brick arch construction which is used in connection with a straight flue sheet;

Fig. 14 is an enlarged sectional view of my improved deflector plate with the associated portion of the firebox door hole; and

Fig. 15 is a front elevation of the deflector plate.

My improved fire-box and combustion chamber construction is particularly suitable for use in connection with locomotives and is so illustrated in the accompanying drawings. Thus it will be seen that I have shown a portion of a boiler 16 of a conventional locomotive which is provided with a fire-box 17 and combustion chamber 18 surrounded by a suitable sheet or wrapper 19. The entrance to the fire-box consists of a conventional type of fire-box door hole

20 and fuel consisting of a relatively finely divided coal is fed through the door hole by means of a conventional automatic stoker 21. Extending across the bottom of the door hole opening and projecting inwardly into the fire-box is a distributor plate 22 which is hollow as shown and is provided with a series of jets 23 through which live steam is forced. The live steam is introduced into the inside of the distributor plate by means of a suitable tube 24 connected to the boiler.

The outlet end of the combustion chamber is provided with a flue or tube sheet 25 to which the ends of a series of tubes or flues 26 are connected. The water in the boiler surrounds the flues or tubes and also the wrapper or sheet of the combustion chamber and fire-box. Extending across the fire-box longitudinally thereof at an angle are a series of arch tubes 27 which are of the usual arcuate shape and communicate at both ends with the boiler.

The combustion chamber, fire-box, and boiler

55

heretofore described are of a conventional type employed in locomotives and serve as an illustration of the type of apparatus to which my invention may be applied. It should be understood of course that my invention may also be used in connection with different types of fire-box, combustion chamber, and boiler construction.

My invention comprises generally an improved deflector plate 28 above the fire-box door hole, an improved brick arch 29 employing a novel and improved type of brick 30 and 30' and also an improved baffle wall 31 formed in the combustion chamber.

The deflector plate 28 may be formed in one or more pieces and is preferably arcuate in form curving downwardly into the fire-box and has a plurality of jets through which live steam is forced. In the form illustrated in the accompanying drawings particularly Figs. 1, 14 and 15 the deflector plate is a unitary casting having a base member 32 with apertures 33 to receive studs 34 for attaching the plate to the wrapper or sheet of the fire-box immediately above the door hole. Supported from the base member 32 is a hollow casting 35 which is arcuate curving downwardly in the manner shown and is preferably provided with external ribs 36. A tube 37 leading from the boiler communicates with the interior of the casting 35 so as to provide live steam which is emitted in jet form through the orifices 38 at the opposite end of the casting. Refractory material may be applied over the base 32 in the manner indicated at 39.

The deflector plate serves several different purposes. Thus it directs the particles of coal downwardly so as to prevent them from impinging against the crown sheet and cutting it at the same time causing more complete combustion of the coal. The fuel is directed by the plate 28 to flow downwardly into the fire-bed under the brick arch 29 toward the rear of the latter, thereby confining the turbulence and retarding the gases. Fuel particles being introduced through the door will not pass directly from the hole over the brick arch by the draught. Also it results in reduced smoke and in a brighter fire. Since the deflector plate also serves to prevent the coal from burning on the distributing plate, the life of the distributing plate is materially increased.

My improved brick arch which is shown more clearly in Figs. 1, 2 and 4-7 comprises a plurality of bricks 30 and 30' supported on the arch tubes 27. The bricks are made of suitable refractory material and are transversely arcuate and of sufficient width to extend between the tubes 27 and be supported thereby as shown in Figs. 2 and 5. The bricks are placed end to end on the tubes 27 with the convex side towards the top and the concave side towards the bottom, thereby forming an arch extending completely across the fire-box. Since no tubes are provided at the extreme sides of the fire-box, I provide suitable means in the form of studs 40 for supporting the rows of bricks on the two sides of the fire-box.

Referring more specifically to the bricks indicated by the numeral 30, it will be seen that they are provided with diagonally extending ribs 41 and 42 on the upper and lower surfaces respectively of the bricks and extending between opposite corners. The side edges of the bricks 30 are cut away and curved in the manner indicated at 43 so as to receive the arch tubes 27. The bricks 30 are so arranged that the ribs 41 and 42 in each longitudinal row are in parallel

relationship. In a transverse direction the ribs of adjacent bricks are arranged in opposite relationship as shown more clearly in Figs. 2, 4 and 5.

5 The bricks 30' are formed with diagonal ribs 42 on their lower concave surfaces. However, instead of the diagonal rib 41 on the upper surface, I provide the bricks 30' with transverse ribs 44 which project upwardly at an angle at the forward ends of the bricks. The bricks 30' are used to form the uppermost transversely extending row as shown in Figs. 1 and 2 while the bricks 30 are used to form the remainder of the brick arch with the exception of a row of plain bricks 30'' which may be used across the base of the arch in the manner shown.

Due to the fact that the bricks are transversely arcuate they may expand when they are heated without distorting or damaging the arch tubes.

20 The diagonal arrangement of the ribs 41 and 42 also permits the same result. The ribs 41, 42 and 44 serve as baffles against which cinders and incompletely combusted particles of fuel impinge. When the force of the particles which engage 25 the lower ribs 42 is broken in this manner they are caused by gravity to fall downwardly on to the fire bed where they have an opportunity to be completely burned. Also the impingement causes the particles to break into smaller particles. The ribs 41 on the upper surface serve to trap the particles and to break them into smaller particles. Rib 44 also serves to imprison the cinders and other particles to break them up into small particles and to cause many of them to 30 fall downwardly onto the fire bed. These ribs also serve to induce a better vacuum for combustion.

The baffle wall which is indicated by the numeral 31 is shown more clearly in Figs. 1, and 40 8-11 and is formed of a series of bricks 45 made of suitable refractory material and having an upper surface which is convex from front to back and concave from end to end. The entire brick is curved from end to end to conform with the 45 curvature of the sheet or wrapper 19 in the combustion chamber. In the small baffle wall shown in Figs. 1, 8 and 9 in which the baffle wall only extends across the lower portion of the combustion chamber the bricks may be held in position by means of T-irons 46 which are spot-welded to the wrapper or sheet. The bricks are provided with inverted T-shape slots 47 to accommodate the T-irons and are attached thereto by means of fire clay.

55 If desired, the baffle wall 31 may be extended completely around the combustion chamber in the manner indicated in Fig. 10 so that a portion of the wall is in inverted position. When this type of wall is employed I prefer to hold the 60 inverted and vertically disposed bricks in position by means of channel irons 48 which are spot-welded to the sheet or wrapper and interengaged with complementary slots 49 formed in the bricks. In this form of brick, fire clay may 65 also be used to attach the brick to the angle irons.

Baffle wall 31 is only employed in that type of construction where the fire-box is provided with a combustion chamber 18. In the form of construction shown in Fig. 13 where the fire-box is 70 provided with a straight tube sheet extending upwardly at the forward end of the arch tubes 27 as indicated at 50, I do not employ a baffle wall 31 but instead I provide the brick arch with a transverse baffle extending across the upper 75 surface thereof a short distance in front of the

tube sheet. This may be accomplished by substituting for the bricks 30 in one of the lower transverse rows of bricks the bricks 30' which have ribs 44 extending upwardly from the front thereof. In the form illustrated in Fig. 13 the second transversely extending row of bricks is formed of bricks 30' whereby a transverse baffle wall is formed by the ribs 44.

The baffle wall 31 in the first form of my invention and the transverse baffle formed by the ribs 44 in the form of my invention shown in Fig. 13 serves to prevent cinders and other particles from impinging against the tube sheets and tubes thereby protecting them from cinder cutting and clogging. Particles engaging the transverse baffle are broken into smaller particles or are imprisoned in front of the baffle.

From the foregoing it will be appreciated that I have provided improved fire-box and combustion chamber construction consisting of an improved deflector plate, improved arch bricks and an improved baffle wall which results in more complete combustion, the elimination of or substantial reduction in cinder cutting and in the prevention of clogging of the tube sheet and tubes.

It should be understood, of course, that many modifications may be made in the illustrated and described embodiments of my invention. As for instance the deflector plate 28 may be supported by the stoker rather than from the fire-box wrapper door sheet. Also in certain instances, such as an oil burner where no brick

arch is employed, the arch bricks may be used as a lining for the fire-box sheet.

I claim:

1. The combination with a fire-box and combustion chamber in which the latter has a wrapper sheet and a tube sheet, of an arch extending within the combustion chamber to form a top wall for the fire-box and to form with the wrapper sheet a bottom wall for the combustion chamber with an opening establishing communication between the fire-box and the combustion chamber, and a baffle wall on the wrapper sheet extending upwardly within the combustion chamber in spaced relation to the tube sheet and the arch and in spaced relation to the top of the combustion chamber.
2. The combination with a fire-box and combustion chamber in which the fire-box has an opening for introducing fuel into the fire-box and in which the combustion chamber has a wrapper sheet and a tube sheet, of a brick arch extending within the combustion chamber to form a top wall for the fire-box and to form with the wrapper sheet a bottom wall for the combustion chamber with an opening establishing communication between the fire-box and the combustion chamber at the front of the combustion chamber, and a brick baffle wall on the wrapper sheet extending upwardly within the combustion chamber in spaced relation to the tube sheet and the arch and in spaced relation to the top of the combustion chamber.

HARRY A. LACERDA.
